Iron Platform for Railway Cars.

No. 243,430.

Patented June 28, 1881.

UNITED STATES PATENT OFFICE.

WILLIAM A. CUSHMAN, OF PROVIDENCE, RHODE ISLAND.

IRON PLATFORM FOR RAILWAY-CARS.

SPECIFICATION forming part of Letters Patent No. 243,430, dated June 28, 1881.

Application filed February 28, 1881. (No model.)

To all whom it may concern:

Be it known that I, WILLIAM A. CUSHMAN, of Providence, in the State of Rhode Island, have invented an Improvement in Iron Platforms for Railway-Cars, of which the following is a specification.

Tubes have been employed in the construction of iron car-platforms.

My present invention relates to the peculiar manner of connecting the iron tubes, and to the combination therewith of wooden end bearers, as hereinafter set forth.

In the drawings, Figure 1 is a side view of part of the platform at one end. Fig. 2 is a section through the tubes and end beam, in larger size. Fig. 3 is a section at *x x*, in larger size, showing the ends of the transverse bearer for the trucks; and Fig. 4 is sections of the iron employed. Fig. 5 is a plan of the tubes at one end of the platform, and Fig. 6 is a cross-section of the same at the line *y y*.

The longitudinal tubes *a a* extend from end to end of the car, and they are kept at proper distances from each other by blocks *b*, and 25 they are tied together by the bands *c*, as heretofore usual.

At the ends of the car-platform there are transverse iron beams *d*, of a **I** shape, and of a width to receive between the horizontal 30 flanges the ends of the horizontal tubes, as seen in Fig. 2, and there are short cup-shaped hubs *h*, that are riveted to the beams *d*, and these are of a size to pass into or around the ends of the tubes *d* and form a strong connection 35 between the tubes and the end beams, *d*, to prevent lateral motion; and there may also be pins inserted transversely through the tubes and hubs to connect them longitudinally.

There is a wooden safety-block, *l*, at the 40 middle of the end of the platform, outside the iron beam *d*, to lessen concussion upon the metal platform, and to leave a space between the beams *d* of two separate cars, and thereby protect the person that couples the cars when 45 they are run together. The draft-beams *m* pass beneath the beam *d* back toward the transom-beam *o* and king-bolt, and these draft-beams *m* are secured by bolts 3 to a draft-plank, *n*, that is above them, and their ends 50 pass in between the flanges of the end beam, *d*, as seen in Fig. 2, so as to secure the draft-

beams to each other and to the iron work of the platform. It is generally preferable to have two of these draft-beams near the longitudinal center of the platform, but at a sufficient distance apart to allow for the introduction of the draft-bar and its springs between them. 55

The transom-beam *o* is made of either **C** or **I** iron, as shown in Fig. 4, and the same passes 60 between the longitudinal tubes *a*; and there are saddles *s* upon the transom-beam, having semicircular recesses for the reception of the tubes, and these saddles are riveted or bolted at 8 to the transom-beam. 65

In some cases the transom-beam may be composed of two iron beams, *o* and *o'*, as seen in Fig. 1, and the beam for the king-bolt be placed between them.

I also make use of longitudinal tie-rod braces 70 *t*, passing horizontally through the beam *l*, along over the transom-beams *o o'*, and down beneath a cross-bearer, near the middle of the cars, below the tubes, and up again over the transom-beam, and to the other end of the car- 75 platform.

In some cases I employ tie-rods *t*³, running through some of the tubes *c* from end to end to insure a firm connection of the end beams, *d*, such tie-rods taking the places of the rivets 80 that secure the hub *h*, as shown in Figs. 2, 5, and 6.

In Letters Patent No. 185,446 an iron end beam is shown with the tubes passing through the same and swelled. This manner of uniting the parts is not sufficiently strong to withstand the concussion to which they are subjected. In my improvement the ends of the tubes abut against the end beam, and the hubs 85 form a very reliable connection of such tubes 90 to the end beam.

I claim as my invention—

1. The combination, with the longitudinal tubes in a car-platform, of the end beam of iron, and the cylindrical hubs fastened to the iron 95 beam and connecting with the ends of the tubes, substantially as set forth.

2. The trough-shaped iron transom-beam, in combination with the longitudinal tubes passing at each side of the transom-beam, and the 100 saddles between the tubes and transom-beam, substantially as set forth.

3. In combination with the metal end beam, *d*, and the tubes *a*, the wooden safety-block *l* outside the beam *d*, the draft-beams *m*, passing beneath the beam *d* and safety-block *l*, and 5 bolted thereto, and the draft-plank *n*, substantially as set forth.

4. The combination, with the iron tubes *a*, iron end beam, *d*, wooden beam *l*, and draft-beams *m*, the tie-rod brace *t*, passing through 10 the end beams over the transom-beam and beneath a bearer, substantially as set forth.

5. The combination, in a metallic car-platform, of longitudinal tubes and the end beams, *d*, with tie-rods passing from end to end through

two or more of the tubes, substantially as set 15 forth.

6. The combination, with the longitudinal tubes in the car-platform, of the transverse iron beam *d*, against which the ends of the tubes abut, and means for connecting such tubes to 20 the metal beam, substantially as specified.

Signed by me this 15th day of February, A. D. 1881.

WM. A. CUSHMAN.
